UNITED STATES PATENT OFFICE.

WILLIAM A. STACEY, OF CHICAGO, ILLINOIS, ASSIGNOR TO THE BRYANT ELECTRIC COMPANY, OF BRIDGEPORT, CONNECTICUT, A CORPORATION OF CONNECTICUT.

PLUG RECEPTACLE.

Application filed June 7, 1922. Serial No. 566,450.

My invention relates to plug receptacles, and the object of my invention is to so construct the receptacles and establish the connections to the contacts thereof that the danger of shock from touching the shell contact incident, for example, to the insertion or removal of a fuse plug or the like, is minimized. The invention is particularly applicable to receptacles such as are commonly employed in fused cut-out blocks, but it is also applicable to lamp sockets, particularly those of the series multiple type.

In the accompanying drawings—

Fig. 1 is a diagrammatic plan of a double pole, double branch fuse cut-out illustrating the wiring connections as heretofore commonly established in a fitting of this type adapted for a three-wire installation;

Fig. 2 is a similar view illustrating the wiring connections in accordance with the present invention;

Fig. 3 is a similar view of a triple pole, double branch cut-out block;

Fig. 4 is a similar view of a triple pole, single branch cut-out block;

Fig. 5 is a diagrammatic view similar to Fig. 2 but adapted to a two-wire system;

Fig. 6 is a view similar to Fig. 5 but illustrating a single branch cut-out; and

Fig. 7 is a diagrammatic illustration of the application of my invention to a double branch plug socket.

In house-wiring installations it is common practice to build up the distribution panel from cut-out blocks having receptacles for plug fuses which protect the branch circuits.

An example of such a double-branch plug cut-out for a three-wire system is illustrated in Fig. 1. Such a three-wire system comprises plus and minus mains 10 and 11, respectively, and a neutral or return main 12, which is grounded. The branch circuit loads 13 and 14 are connected to these leads through plug fuses inserted in the receptacles 15 and 16. The construction of these so-called branch blocks is universally that indicated in Fig. 1, in which the connections 17 and 18 from the mains are led to the center contacts 20 and 21 of the receptacles, while the connections 22 and 23 to the loads 13 and 14 of the branch circuits are connected to the screw shells 24 and 25 respectively of the receptacles. In order to balance the loads on the mains, the connection is made from one of the receptacles on each side of the block, to

the grounded main 12, while the connection to the other receptacle is made on one side of the block to the positive main, and on the other side to the negative main.

If the load 14 is too great, one or the other, or both, of the fuses in the receptacles 15 and 16 will burn out, and to re-establish the circuit it is necessary to insert a new fuse, or new fuses. This involves unscrewing of the fuse plugs from the receptacles and the screwing in of the new plugs, with the consequent possible danger, in both operations, that the attendant's fingers may come in contact with the projecting screw shells 24 and 25 of the receptacles. If the fuse in the receptacle 16 is intact while the fuse in the receptacle 15 has been ruptured, the connection from the screw shell 24 of the latter through the branch connections 22-23, shell 25, fuse in the receptacle 16, center contact 21 and connection 18 is established to the ground lead 12. Consequently, there is little danger of injury to the attendant even should the fingers touch the screw shell 24 during this operation.

On the other hand, if the fuse in the receptacle 16 is defective while the fuse in receptacle 15 is intact, the connection to the screw shell 25 of the receptacle 16 is established with the live main 10 through the receptacle 15, and the load 14. Consequently, if the attendant, during the renewal operation, touches the screw shell 25, the current passes to ground through the attendant and shock results.

The modification of construction which I propose, contemplates the connection of the screw shells of both receptacles to the ground side of the line, and the connection of the relatively inaccessible center contacts to the live main. This is illustrated in the double-branch, two-pole, three-wire system in Fig. 2. This is readily accomplished by establishing the connection between the ground 12 and the screw shell of one of the pair of receptacles 100 in each branch circuit, instead of following the usual practice of connecting the ground to the center contact of that receptacle. When this arrangement is employed it is clear that contact with the screw shell of any of the receptacles results in no danger of shock, since all are grounded. Thus, not only may the grounded shell 25 of receptacle 16 be safely touched, but if the fuse in receptacle 15 is defective and must be renewed, while the fuse 110

in receptacle 16 is intact, the screw shell 24 of receptacle 15 is nevertheless connected to ground through the fuse in the receptacle 16.

The same idea may be carried out in a 5 double-branch, three-pole, three-wire system, as shown in Fig. 3. In this modification the leads from the live plus and minus mains 10 and 11 are connected to the center contacts 26 and 27 of the receptacles balanced on opposite sides of the circuit, while the connection from the load 28 is returned through the center contact 29 of its fuse receptacle connected through the cooperating screw shell 30 to the ground main 12. It is obvious that the 15 screw shells 31 and 32 of the receptacles, the center contacts of which are connected to the power lines 10 and 11, are always grounded through the return branch 33.

In Fig. 4 the same arrangement is indicated for a single-branch, triple-pole, three-wire cut-out block.

In Fig. 5 the same idea is embodied in a two-wire, double-branch cut-out. As will be seen, the connection from the live main 34 is 25 established to the center contacts 35 on one side of the branch line, while the ground line 36 is connected to the screw shells 37 of the receptacles on the return side of the branch circuit.

30 The same thought is applied in Fig. 6 to the single-branch, double-pole, two-wire cut-out.

As above mentioned, the invention is applicable also to multi-lamp-socket fittings 35 where the sockets are arranged in series. I have indicated in Fig. 7 a twin plug socket embodying the idea. The screw shell 38 of

the plug is indicated as connected to ground, and the center contact 39 to the incoming live wire. The connection from the center contact 39 of the plug is established to the center contact 40 of one receptacle, and from the shell 41 of the latter to the center contact 42 of the second receptacle, while the screw shell 43 of the latter is connected to the grounded screw shell 38 of the plug. It is thus obvious that the screw shells of both lamp sockets are connected to ground and may be touched by the attendant without danger of shock.

The idea may be applied to various other 50 fittings, those illustrated being merely illustrative embodiments of what I claim as my invention. I have not shown any particular structure for establishing these connections, since this is subject to many modifications 55 well understood by those skilled in the art.

I claim—

In an electric wiring system having a group of feed mains, one of which is grounded, an electric cut-out block having an insulating 60 base, a pair of receptacles mounted on said block, each of said receptacles comprising shell and center contacts, a load connected between the shell contact of one receptacle and the center contact of the second receptacle, means establishing connection between the shell terminal of one receptacle and the grounded main, and a connection between the center contact of the other receptacle and a live main.

In testimony whereof I have signed my name to this specification.

WILLIAM A. STACEY.
